Attorney.

UNITED STATES PATENT OFFICE.

ARTHUR L. HAWKESWORTH, OF BUTTE, MONTANA.

DRILL.

1,426,637.

Specification of Letters Patent. Patented Aug. 22, 1922.

Application filed November 21, 1921. Serial No. 516,782.

To all whom it may concern:

Be it known that I, ARTHUR L. HAWKESWORTH, a citizen of the United States, residing at Butte, in the county of Silverbow 5 and State of Montana, have invented certain new and useful Improvements in Drills, of which the following is a specification.

The present invention has relation to improvements in drills having detachable bits, 10 the object sought being to provide simple and effective interlocking means between the bit and shank whereby the bit may be retained in place while in working position.

A further object is to provide a drill having 15 a bit that will present a minimum rubbing surface against the drilled hole, which surface will not appreciably increase as the bit wears. Another object sought is to form the cutting edges of the bit in such manner 20 that they will retain their cutting efficiency even after they have become considerably worn down. Other advantages will be better apparent from a detailed description of the invention in connection with the accompanying drawings in which—

Figure 1 is an elevation of the drill turned to present the small end of the cooperating tongues and grooves on bit and shank; Fig. 2 is a side elevation of the drill; Fig. 3 is an 30 elevation turned through an angle of 45° or midway between the positions shown in Figures 1 and 2; Fig. 4 is a detached elevational view of the bit turned to present the narrow ends of tongue and groove; Fig. 35 5 is a detached elevational view of the shank turned to present the narrow ends of tongue and groove which cooperate with tongue and groove of the bit to hold the same in place; Fig. 6 is a bottom plan of the bit; Fig. 7 40 is an end view of the shank showing in plan the formations that interlock with those on the bit; Fig. 8 is a top plan of the bit showing the arrangement of the cutting edges.

Referring to the drawings, 1 represents 45 a drill bar or shank provided with a central passage-way or duct α for the flow of water usually employed in drilling operations as well understood in the art. The shank is provided at its bit supporting end with a 50 transverse dove-tail tongue 2 disposed across the shank to one side of the axis thereof, and a transverse dove-tail groove 3 adjacent to the tongue and on the other side of said axis. The side walls of the tongue taper 55 in the general direction toward the cutting end of the drill, and the side walls of the

groove taper in the opposite direction or away from the cutting end of the drill. The tongue and groove have the bounding wall b in common, which is substantially twice the 60 width of the outer bounding wall c of the tongue and outer bounding wall d of the groove, the wall c being determined by the offset e , and the wall d by the top face f thereof, said offset e and top face f being in 65 the same plane, which is parallel with the bottom face g of the groove and top face h of the tongue.

Adapted to be passed across the shank 1 is the bit 4, the same being provided with two 70 converging ducts a' , a' , said ducts coming together at their intersection with duct a of the shank when the bit is in working position on the shank. The bit is provided with a transverse tongue 5 shaped to fit groove 3 75 of the shank and a transverse groove 6 shaped to receive tongue 2 of said shank. The tongue 5 and groove 6 have the bounding wall i in common, said wall extending across the axis of the drill. The outer 80 bounding walls j of the tongue and k of the groove, however, are about one-half the width of wall i , being determined by the plane of offset m and top face n of wall k , said offset and top face being in a common 85 plane parallel with the bottom face p of the tongue 5 and top face r of the groove 6. From the foregoing the tongue and groove formations on shank and bit will be seen to be exact counterparts of each, being 90 reversed, however, to permit their engagement one with the other. This engagement may be readily accomplished by simply slipping the narrow end of tongue 5 into the wide end of groove 3, whereupon the narrow end 95 of tongue 2 will enter the wide end of groove 6. The bit may now be moved across the axis of the shank until the tongues are wedged into their corresponding grooves, at which time the top faces f and n will bear 100 against the offsets m and e respectively, and the shank and bit are in operative relation. Obviously the exact details of the above construction need not be adhered to, as they may be modified without departing from the 105 spirit of the invention. By virtue of the inclination of the tongues and grooves on both shank and bit, said bit will be wedged tighter as the drill is in operation, however, in order to detach the same it is merely necessary to give a slight knock on the bit at 110 the narrow end of tongue 5 to loosen same,

whereon it may be readily removed and a new bit substituted.

The bit 4 is formed with a series of cutting legs 7 (four in the present case) said legs extending down a short distance onto the shank 1 and terminating at their outer ends in beveled cutting edges 8. Recesses *t* are formed between the cutting edges so as to extend the cutting edges inwardly a considerable distance, thus providing a thin wall *w* that will retain its cutting efficiency as it wears down, and give the bit a longer period of usefulness before going to the shop for sharpening. If the recesses *t* were not provided and the bevel surfaces *u*, *u* continued until they intersect, the cutting edge would continually get wider as it became worn, and would soon cease to cut. In the present construction the cutting edge cannot get wider than the thickness of the wall *w* between the recesses *t* until the wall has been entirely worn away. The peripheral surfaces of the cutting legs are dished out or concave at *v* so that after the bit has become worn there will be less friction against the sides of the hole than there would be if the depressions were omitted. With the legs 8 dished the friction would only exist around the edges of the legs instead of over the entire surface.

The recesses *t* also result in the formation of circumferentially extending wings *w'*, *w'*, at the ends of the cutting legs 7, said wings assisting in drilling the hole when the drill is operated by percussion.

Having described my invention, I claim:

1. In combination with a shank terminating at one end in a tapering tongue and having a tapering groove adjacent to the tongue, the tongue and groove being on opposite sides of a plane passing through the axis of the shank a cutting tool movable across the axis of the shank and provided with a groove and tongue adjacent thereto for cooperating with the tongue and groove on the shank when tool and shank are in operative relation.

2. In combination with a shank terminating at one end in a tongue disposed on one side of a plane passing through the axis of the shank, the side walls of said tongue tapering in the general direction away from the shank, a groove formed in the shank adjacent to the tongue and on the opposite side of said tongue, the side walls of said groove tapering in the general direction

toward the shank, a cutting tool movable across the axis of the shank and provided with a groove and tongue for cooperating with the tongue and groove on the shank 60 when tool and shank are in operative relation.

3. In combination with a shank terminating at one end in a dove-tail tongue, the side walls of which taper in the general 65 direction away from the shank, said tongue and groove being disposed on opposite sides of a plane passing through the axis of the shank, a dove-tail groove formed in the shank adjacent to the tongue, the side walls 70 of said groove tapering in the general direction toward the shank, a cutting tool movable across the axis of the shank and provided with a groove and tongue for cooperating with the tongue and groove on 75 the shank when tool and shank are in operative relation.

4. In combination with a shank terminating at one end in a tapering tongue and having a tapering groove adjacent to the 80 tongue, a cutting tool movable across the axis of the shank and provided with a groove and tongue adjacent thereto for cooperating with the tongue and groove on the shank when tool and shank are in operative relation, the outer bounding wall of the groove being of lesser dimension than the inner wall thereof, and the outer bounding wall of the tongue being of lesser dimension than the inner wall thereof. 90

5. A drill bit provided with a plurality of cutting legs, the bit being recessed between said legs to form comparatively thin walls at the ends of the legs, the outer ends of said walls forming cutting edges, and the peripheral surfaces of said legs being recessed. 95

6. A drill bit provided with cutting legs terminating at their outer ends in cutting surfaces having circumferentially extending wings the peripheral surfaces of said legs being recessed. 100

7. A drill bit provided with cutting legs terminating at their outer ends in cutting surfaces having circumferentially extending wings, the bit being recessed between the legs and the peripheral surfaces of said legs being recessed. 105

In testimony whereof I hereunto affix my signature.

ARTHUR L. HAWKESWORTH.
